**ADA E. FARMER, OF PROVIDENCE, RHODE ISLAND, ASSIGNOR TO C. G. KING & CO., INC.,
OF PROVIDENCE, RHODE ISLAND**

DESIGN FOR A SHOE BUCKLE

Application filed July 11, 1931. Serial No. 40,502. Term of patent 7 years.

To all whom it may concern:

Be it known that I, ADA E. FARMER, a citizen of the United States, residing at Providence, in the county of Providence and State of Rhode Island, have invented a new, original, and ornamental Design for Shoe Buckles, of which the following is a specification, reference being had to the accompanying drawings, forming part thereof.

In said drawings, Fig. 1 is a front face view,

and Fig. 2 is an edge view of a shoe buckle, showing my new design.

I claim:

The ornamental design for a shoe buckle as shown.

Signed at Providence, in the county of Providence and State of Rhode Island, this 10th day of July, A. D. 1931.

ADA E. FARMER.
